FISH LURE

Ferdinando A. Guardia, 4746 Homer Ave. SE.,
Suitland, Md.

Filed Oct. 5, 1965, Ser. No. 87,320

Term of patent 14 years

(Cl. D31—4)

FIGURE 1 is a perspective view of a fish lure showing my new design with hooks and rings shown in phantom;

FIGURE 2 is a front view thereof;

FIGURE 3 is a rear view thereof;

FIGURE 4 is a top view thereof;

FIGURE 5 is a bottom view thereof;

FIGURE 6 is a side view thereof, the side opposite FIGURE 6 being the same as that shown in FIGURE 6;

FIGURE 7 is a side view modification of the fish lure shown in FIGURES 1 to 6.

The broken line showing representing the hook and ring member is shown for illustrative purposes only.

I claim:

The ornamental design for a fish lure, as shown and described.
